UNITED STATES PATENT OFFICE.

LEO JESSEL, OF DETROIT, MICHIGAN.

PERMUTATION-LOCK.

SPECIFICATION forming part of Letters Patent No. 244,459, dated July 19, 1881.

Application filed April 22, 1881. (Model.)

To all whom it may concern:

Be it known that I, LEO JESSEL, of the city of Detroit, county of Wayne, and State of Michigan, have invented an Improvement in Locks, of which the following is a specification.

My invention relates to what are known as "combination" or "permutation" locks; and it consists in arranging two or more tumblers or disks provided with slotted flanges and operated from one or more places with one or more bolts; further, in a casing or covering to the disks constituting the handle, wherewith to control the movement of the tumblers, whereby the movements of said disks are wholly protected from view when being manipulated to open the door; and in minor details of construction, all of which are fully set forth in the following specification, and shown in the accompanying drawings, which form part thereof.

Heretofore locks of this class have had the tumblers arranged one above the other, making a thicker lock and one which requires more care in opening, owing to the liability of the displacement of the tumblers.

The object of my invention is to construct a lock having a series of tumblers controlling one or more bolts, each of said tumblers being arranged separately and distinctly, having its own bearings and controlling the movement of a different part of the same or another bolt.

In the drawings, Figure 1 is a sectional elevation of my improved lock, having a single bolt on the line $y y$. Fig. 2 is a sectional plan of same on line $x x$. Fig. 3 is a vertical cross-section of same on line $z z$. Fig. 4 is an elevation of the permutation-handle with the top of the protecting-casing broken away. Fig. 5 is a perspective view of one form of the tumblers and part of the lock-frame and bolt. Fig. 6 is a plan view of the top of the tumbler directly under the permutation-handle. Figs. 7 and 8 are modified forms of casing to protect the permutation-handle. Fig. 9 is a plan view, showing arrangement of lock with double bolts.

A is the frame or case, and B is the cover of same. Upon the cover, and forming part of the same, are two or more circular bearings, D D' D², which support and carry the flanged disks N N' N². The parts D D' D² are provided with a passage-way for the bolt F, and slots or openings δ on one side for the passage of the lugs or projections F', and upon their

circular edge with a deep groove, d' . The flanged tumbler-disks N N' N² have thin flanges d^2 , provided respectively with slots n , which register at the opening of the lock with the opening d in the circular bearings to allow the passage of the projections F'. It is not necessary that there shall be a groove, d' , as the outer flange alone would guide the tumblers and protect their flanges carrying the slot n from being detected by feeling, in case it were attempted to pick the lock. The tumbler or disk N is rotated direct by the spindle O and its operating-disk O'. In order that the combination may be changed I secure upon the end of the spindle O a toothed wheel, S, having as many teeth T as there are indicator-points on the permutation-disk. It is set in a recess in the top of the tumbler N, which is provided with a single tooth or projection, t, which may correspond to the opening or slot n . By changing the position of wheel S with disk N the combination may be readily changed. The loose sleeve P carries the operating-disk P' on one end and the spur-wheel M on the other, which spur-wheel operates the tumbler N' by means of the spur-wheel M'. The outer sleeve, Q, provided on one end with the permutation-disk Q' and on the other with the spur-wheel I, works the tumbler N² by means of the spur-wheels I' and I². The combination can readily be changed by means of these spur-wheels, and without the least trouble or inconvenience, by disconnecting them and turning one or both around to any extent and bringing the teeth to mesh again, when it will be found a new number, letter, or projection will be required to open the lock, so far as that tumbler is concerned.

The operating-disks O', P', and Q' are provided about their peripheries with a number of small points or eminences, p', and each is provided with a single longer and more pointed projection, p. These disks, constituting the permutation-handle, are inclosed by a casing or cover, R, having one or more openings, r, through which the finger or fingers may rotate the disks, and yet prevent any one standing by from seeing the combination. This casing R may be made as shown in Fig. 8, in which there are two openings, r, the upper of which is designed to allow the disks to be rotated, and the lower for the insertion of a finger to

feel, set, and hold the disks in their proper position when set to prevent displacement of one disk upon operating the next. The caps R' protect the disks from rain.

5 The view shown in Fig. 7 is a modification of Fig. 8, the fingers being placed on the sides, instead of at the top and bottom.

The bolt F is pressed out by a spring, H, and drawn back by lever G oscillated by handle G'.

The lock may be applied to a drawer or door. In the latter case it would be advisable to be able to operate the tumblers and bolt from both sides.

15 If desired, a separate operating disk or handle may be used to each tumbler.

The operation of the single-bolt lock is as follows: The disks O', P', and Q' being set with the long points p in position with the finger resting upon them, they are rotated one at a time until the proper number of pins or projections p' are counted from the long pointed projection p, then the finger holds that disk and the same operation is performed on each 25 and every disk. These manipulations cause the tumbler-flanges d' to be rotated until the slots n are in the right position to register with the slots d in the bearings. The handle G' is then turned and the bolt F withdrawn from 30 the catch F', the projection F' passing through the slots n and d. The door C is then open. To keep the lock open any ordinary latch may be used, or one tumbler may be rotated slightly, and the projection F is then located on the opposite side of the flange d' and holds the bolt back. When arranged for two or more bolts, 35 where great security is required, it is made as shown in Fig. 9, in which the tumblers are arranged about a central operating compound

40 stem, X. By this arrangement the safety is greatly increased, for the operating-disks may be set in order; but the central stem may operate tumbler 1, central sleeve, 2, may operate tumbler 5, sleeve 3 may operate tumbler 3, and 45 so on, it being so mixed that it would be a difficult task to find out which disks operate a particular bolt. By arranging the tumblers separately by themselves I can make a lock of less thickness and one having greater security; also, each tumbler may be changed so 50 far as its position in the lock is concerned, as well as the disks being set for a new combination, therefore the number of combinations such a lock is capable of making is enormous.

55 I do not confine myself to the particular shaped tumbler, as it may be modified somewhat to take up less space.

When two bolts are used one operating-disk

may be made to rotate two tumblers, one on each bolt. By this arrangement only one-half as many disks will be required, and it will be absolutely necessary to open one bolt before operating on the other; and with this construction it will be found a very difficult task to perform if the combination for each bolt is not known.

Having now described my invention, what I claim as new, and desire to secure by Letters Patent, is—

1. In a combination-lock, the frame A and cover B, a single bolt, F, provided with projections F', or their equivalent, and two or more tumblers provided with slots n, rotating in the same plane before said projections F', as and for the purpose specified. 75

2. In a combination-lock, the frame A, cover B, bearings D D' D'', provided with slots d, tumblers N N' N'', provided with slots n, and bolt F, provided with projections F', in combination with central stem, O, and sleeves P 80 and Q, provided on the ends with operating-disks O' P' Q', spur-wheels M M' and I, I', and I'', and means to operate the bolt, as and for the purpose specified.

3. The permutation - handle, consisting of 85 disks having their peripheries provided with projections, in combination with a cap or easing covering said handle, said easing being provided with apertures or openings whereby to rotate said disks with the fingers, as 90 and for the purpose specified.

4. In a combination-lock, the permutation-handle, in combination with a casing, R, provided with slots or openings r, arranged on opposite, or nearly opposite, sides of said casing, 95 one of which openings is larger than the other, and permutation-disks, each provided with one long point and a number of smaller projections, as and for the purpose specified.

5. In a combination-lock, the permutation-handle consisting of a series of disks or rings arranged one above the other, each of said rings being provided with one long point, and a series of small projections arranged about their peripheries, as shown and described. 100

6. The combination of bearing D, provided with slot d and groove d', tumbler N, provided with flange d'' and slot n, and bolt F, provided with a projection, F', as and for the purpose specified. 105

In testimony of which invention I hereunto set my hand.

LEO JESSEL.
